ABSTRACT: The invention provides a ventilating fan unit insertable into an opening in a windowpane or the like partition and adapted to propel air from the outside atmosphere into a ventilated interior and at the same time to exhaust air from the ventilated interior to the outside atmosphere, which comprises two half shells which cover the outside and inside respectively of said opening and bear with their peripheral edges against opposite sides of the edges thereof to form a gas and liquid-tight joint. Each shell is formed with a central recessed portion the floors of which are detachably connected back to back. To said floors a common fan motor is affixed, the two shaft ends of which extend axially into the recessed portions where they carry flow fans. Each fan propels an air stream in countercurrent to the other. The recessed portions are formed with nozzles projecting from the periphery of said portions and extending through the opening in the partition.

VENTILATING FAN UNIT

BACKGROUND OF THE INVENTION

This invention relates to ventilating fan units, and more specifically to a ventilating fan unit insertable into an opening in a window pane, in a wall or other partition.

SUMMARY OF THE INVENTION

It is the object of the present invention to provide a ventilating fan unit of the aforescribed type, in which the turbulent streams that still occur in conventional fan housings are widely eliminated and the streams are given a regular flow path.

To attain this object, the present invention provides a ventilating fan unit insertable into an opening in a windowpane, in a wall or other partition and adapted to propel air from the outside atmosphere into a ventilated interior and at the same time to exhaust air from the ventilated interior to the outside atmosphere, comprising a fan housing composed of two half shells covering the outside and inside respectively of said opening and bearing with their peripheral edges against opposite sides of the edges thereof to form gastight and liquid-tight joints, a central recessed portion with a floor at its base formed in each of said half shells, the floors of said two recesses being detachably connected back to back approximately in the plane defined by the abutting peripheral edges of said half shells, a fan motor affixed to said floors, and having oppositely projecting shaft ends each of which extends axially into one of said recessed portions, a flow fan secured to each of said shaft ends and adapted to propel an airstream in countercurrent to the other airstream through said fan housing in separate paths, and at least one nozzle extending from the periphery of the recessed portion in each of the half shells through the opening in the partition into and through the other half shell.

Advantageously, each of the cylindrical recessed portions may be formed with at least two nozzles projecting from the periphery of said portion, the nozzles of one recessed portion crossing the nozzles of the other recessed portion in the opening in the partition so that the nozzles of each recessed portion convey air from the one side to the other side of said partition.

If a relatively small increase in depth of the ventilating fan unit is put up with, all resistances against the flow of the streams can be overcome and the air stream generated by the two flow fans can be considerably increased.

In an advantageous embodiment, such increase is attained in that the fan motor together with the flow fans mounted on the ends of the motor shaft as well as the recessed portions together with their nozzles are inclined within the fan housing with respect to the plane of the partition so that the nozzles project in the exact centrifugal direction of the flow fans and extend through the opening in the partition in opposite directions.

Other features of the invention will be understood as the following particular description of embodiments of the invention shown in the accompanying drawings proceeds.

BRIEF DESCRIPTION OF THE DRAWINGS

Several embodiments of the invention will now be described by way of example and with reference to the accompanying drawings, in which:

FIG. 1 is a longitudinal section through a ventilating fan unit according to the invention;

FIG. 2 is a perspective view showing the cylindrical recessed portions, each of which has one nozzle and which are mounted in the opening in a windowpane;

FIG. 3 is a perspective view similar to FIG. 2 but showing each of the cylindrical recessed portions provided with two nozzles; and

FIG. 4 is a longitudinal section through a ventilating fan unit in which the drive members of the unit are arranged in inclined position with respect to the plane of the windowpane.

DESCRIPTION OF THE PREFERRED EMBODIMENTS

The ventilating fan unit proposed by the invention generally comprises two half shells 10 and 11 of a fan housing which are so affixed to the inside and outside respectively of a corresponding opening 28 cut into a window pane 21, wall or like partition that the edges of the two half shells 10 and 11 abut each side of the edges of the opening 28 in the windowpane 21 and thus, with the interposition of sealing rings, form a gastight and liquidtight joint.

Each half shell 10 and 11 is formed with a central cylindrical recessed portion 12 and 13 respectively, and the periphery of each recessed portion is formed with radially projecting nozzles 22 and 23.

In the embodiment illustrated in FIG. 2 each of the recessed portions 12 and 13 is formed with one nozzle 22 or 23, respectively, only. In the vicinity of the circumference of the recessed portions 12 and 13, each of the nozzles 22 and 23 is bent to extend across the width of the periphery of the adjacent recessed portion if the floors of the two recessed portions are connected together. However, as shown in FIG. 3, more than one, for example two projecting nozzles 22 and 23 may be arranged to extend across the width of the periphery of each of the recessed portions 12 and 13, said embodiment being particularly suitable for attachment to a roof. The nozzles 22 of one recessed portion 12 cross the nozzles 23 of the other recessed portion 13 in the area of the opening 28 in the windowpane 21 or like partition so that in both cases a passage 30 of the air streams from one to the other side of the partition is ensured without mutual interference between the two streams. Openings 14 are arranged in the floors of the recessed portions 12 and 13 and serve to accommodate a fan motor 15, the shaft ends of which project into the recessed portions 12 and 13 where they carry flow fans 16 and 17. The flow fans 16 and 17 draw in air through lattices 26 or 27 or the like and propel it through the nozzles 22 or 23 to the respective other side of the partition. The passage of air through the nozzles 22 and 23 may be fully or partly throttled by throttling means in the form of flaps or slides 18 that can be brought into the nozzle cross section. Furthermore, the nozzle ends may receive replaceable filter or electrical heating means. It should be noted that the recessed portions 12 and 13 together with their nozzles 22 and 23 have the same dimensions and may be produced in one and the same mold so that they may be replaced by each other. The nozzles 22 and 24 are provided with bearings 19 and 20 which rest on the edge of the opening in the partition 21 so that the ventilation openings 24 and 25 of the half shells 10 and 11 are in alignment with the nozzle ends when the half shells of the fan housing are in operative position.

FIG. 4 illustrates a particularly advantageous embodiment in which the fan motor 15 as well as the two flow fans 16 and 17 mounted on the ends of the motor shaft are so arranged within the fan housing formed by the two half shells that they are inclined with respect to the plane of the partition or window pane 21. The cylindrical recessed portions 12 and 13 embracing said flow fans 16 and 17 and the nozzles 22 and 23 are also inclined. In this embodiment, the nozzles 22 and 23 extend in the exact centrifugal direction of the flow fans 16 and 17 and pass in opposite direction through the partition 21 so that the airstreams generated by the flow fans flow directly, i.e. without having to take up with any obstacle or deflection, into the interior and the exterior of a room, respectively.

We claim:

1. A ventilating fan unit insertable into an opening in a windowpane, in a wall or other partition and adapted to propel air from the outside atmosphere into a ventilated interior and at the same time to exhaust air from the ventilated interior to the outside atmosphere, comprising:
a. a fan housing composed of two half shells covering the outside and inside respectively of said opening and bearing with their peripheral edges against opposite sides of the edges thereof, to form gastight and liquidtight joints;

- b. a central recessed portion with a panel at its base formed in each of said half shells, the panels of said two recessed portions being detachably connected back-to-back approximately in the plane defined by the peripheral edges of said half shells;
  - c. a fan motor affixed to both said panels and having a shaft transverse to said plane with the oppositely projecting shaft ends each extending axially into one of said recessed portions,
  - d. a flow fan in each of said recessed portions secured to each of said shaft ends and adapted to propel an airstream in countercurrent to the other airstream through said fan housing in separate paths; and
  - e. at least one duct extending from the periphery of the recessed portion in each of the half shells through the opening in the partition into and through the other half shell.
2. A ventilating fan unit as claimed in claim 1, where each of the recessed portions is formed with at least two ducts projecting from the periphery of said recessed portion, the ducts of one recessed portion crossing the nozzles of the other recessed portion in the opening in the partition so that the ducts of each recessed portion convey air from the one side to the other side of said partition.

- 3. A ventilating fan unit as claimed in claim 1, comprising throttling mechanisms in the ducts in the half shells for at least partly shutting off said ducts, said ducts being controlled by common actuating means.
- 5. 4. A ventilating fan unit as claimed in claim 1, comprising replaceable filter means in the ends of the ducts.
- 5. A ventilating fan unit as claimed in claim 1, comprising electrical heating means in the ends of the ducts.
- 6. A ventilating fan unit as claimed in claim 1, wherein the recessed portion of the one half shell together with its duct has the same size as the recessed portion of the other half shell together with its duct, both recessed portions being replaceable by each other.
- 10 7. A ventilating fan unit as claimed in claim 1, wherein the ducts constitute bearings resting on the edge of the opening in the partition.
- 15 8. A ventilating fan unit as claimed in claim 1, wherein the fan motor together with the flow fans mounted on the ends of the motor shaft as well as the recessed portions together with their ducts are inclined within the fan housing with respect to the plane of the partition so that the ducts project in the exact centrifugal direction of the flow fans and extend through the opening in the partition in opposite directions.
